(57) **CLAIM**

The ornamental design for a watering hose repairer connector, as shown and described.

DESCRIPTION

FIG. 1 is a perspective view of our watering hose repairer connector according to our new design;
 FIG. 2 is a front elevation view thereof;
 FIG. 3 is a rear elevation view thereof;
 FIG. 4 is a right side elevation view thereof;
 FIG. 5 is a left side elevation view thereof;
 FIG. 6 is a top plan view thereof; and,
 FIG. 7 is a bottom plan view thereof.

The perspective view of FIG. 1 shows an interior of the watering hose repairer connector that is rotationally symmetric as shown in FIG. 2.
